UNITED STATES PATENT OFFICE

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS

MINING MACHINE

Application filed February 14, 1921, Serial No. 444,767. Renewed April 20, 1929.

This invention relates to mining machines and has for its object to provide a new and improved device of this description. The invention has among other objects to provide a mining machine which can be easily and quickly handled during its operation and during its movement from place to place.

The invention has among other objects to provide a mining machine which has a main frame, preferably mounted upon wheels, and a cutting element separate from this main frame with a controlling connection between the cutting element and the main frame, this controlling connection arranged so that it can lift and lower the cutting element and so that it can move the cutting element laterally while it is cutting, and the device may further be arranged so that the controlling connection while the machine is cutting does not support the machine, but only moves it laterally, the machine being supported upon the floor of the mine, and being free to follow any unevenness of the floor, said machine being, during the cutting movement, independent of any vertically acting support. This controlling connection may thus be used to lift the machine and carry it to the point of use and lower it to the floor and then the lifting action may cease and the machine be supported on the floor, thus giving it great freedom of movement so that it may cut around stones and other hard obstacles instead of cutting through them and may follow the floor of the mine whatever its form, shape, contour or arrangement may be.

This invention permits a mining machine separate from a main frame or truck to be handled as though it were on the truck, and yet makes it unnecessary to unload it from the truck when being operated or load it on the truck when being carried from point to point.

The invention has other objects which are more specifically pointed out in the specification and claims hereto attached.

In the drawings I have illustrated one form of my invention, wherein

Fig. 1 is a side elevation of a machine embodying the invention with the front end removed;

Fig. 2 is a view of the front end of the mining machine removed from Fig. 1, a portion of the cutter being omitted;

Fig. 21 is a view showing the machine after the lateral cut has been made, with the parts in position to make the final cut by moving the cutter rearwardly;

Fig. 22 shows the machine in position to start the cut when in a narrow entry;

Fig. 23 is a view showing the method of using the machine as a longwall machine.

Like numerals refer to like parts throughout the several figures.

In carrying out my invention I provide a machine having a frame 1, mounted upon wheels 2. The frame 1 constitutes a main supporting frame. A movable frame 3 is movably mounted in position. As shown in Fig. 7 the movable frame 3 is provided with a hub 4 which fits on a projection 5 on the frame 1, the moving frame rotating about this projection. Mounted on the frame 3 are two supporting arms 6, said supporting arms being movably mounted, and being connected with a cutting element 7, and arranged so that this cutting element may be moved to various positions. The supporting arms may be arranged in any desired manner, and as herein shown (see Figs. 2, 4 and 15), these supporting arms are connected to the ends of a rod or shaft 8, which is arranged so that it may be turned for adjustment. The ends of the supporting arms 6 are shown split and they surround the ends 9 of the rod or shaft 8. These ends 9 are eccentric with the body portion 10 of said rod or shaft, said body portion 10 working in a bearing 11 pivoted to the frame of the cutting element by being mounted on the pivot 12 (see Fig. 16) so that the rod or shaft and its bearing may be adjusted. The cutting element is provided with a cutter arm 13, and this eccentric construction of the rod or shaft 8 is for the purpose of adjusting this cutter arm by raising or lowering its outer end so that its longitudinal axes is paralleled with the floor when the cutting element is lifted or lowered by the arms 6. When for example the arms 6 are lifted or lowered this movement tends to move the cutter arm so that it will not be longitudinally parallel with the floor, and it is then moved parallel with the floor by rotating the shaft or rod 8, the eccentricity of the main body 10 and the ends 9 being such as to secure this result.

If for any reason the cutter arm has one edge higher than the other, that is is not parallel laterally with the floor, this parallelism is secured by moving the shaft 8 and its bearing about the pivot 12. This is done by means of the adjusting screws 14 which are threaded into the projections 15 on the frame of the cutting element, and which engage the bearing 11 of the rod or shaft 8 (see Fig. 16). It will thus be seen that by this means the cutter arm may be adjusted so that it will be longitudinally and laterally parallel with the floor along which the cut is made.

The supporting arms 6 as herein shown are connected with a rock shaft 16 (see Figs. 1, 3 and 4). This rock shaft is mounted in bearings 17 on the movable frame 3, these bearings being preferably carried by the upper standing parts 18 so as to permit the driving shaft for the cutting element to pass under the rock shaft 16. This rock shaft 16 is rocked so as to lift and lower the arms 6 in any desired manner. As herein shown a controlling arm 19 is connected with the rock shaft 16 (see Fig. 3), and this controlling arm is manipulated by suitable mechanism to raise and lower the supporting arms and the cutting element. One form of mechanism for this purpose is herein illustrated. In this construction (see Figs. 3 and 6), the arm 19 is provided with a socket or hub 20 at one end which surrounds a rotating part 21, which in this instance is screw threaded. A nut 22 is mounted on the threaded rod 21 so as to be raised and lowered when the rod is rotated. This nut is prevented from rotating by some suitable means, such for example as the projections 23, which slide along the stationary guide 24. It will thus be seen that when the threaded rod is rotated in one direction, the nut 22 is raised and the weight of the cutting element will cause it to be lowered. When the threaded rod 21 is rotated in the opposite direction the nut 22 will be lowered and this will press down the end of the controlling arm 19 and rock the shaft 16 and lift the cutting element. The threaded rod 21 is rotated in any suitable manner. As herein shown it is mounted in bearings 25 in the moving frame, and is driven by the motor 26 mounted on said moving frame. The motor is shown as an electric motor, and its armature shaft 27 is provided with a pinion 29. The pinion 29 engages a gear 30 (see Figs. 3 and 9), mounted on the shaft 31. This shaft has a pinion 32 which engages a gear 33 mounted on the shaft 34. The shaft 34 has a pinion 35 which engages a gear 36 loosely mounted on the shaft 40. This gear 36 is connected at one end to one member 38 of a slip clutch. The other member 39 of this slip clutch is connected to a shaft 40. The two members of the slip clutch are pressed together by the springs 41, this connection being arranged so that when too great a strain occurs at any point, the clutch will slip and prevent breakage.

The shaft 40 is provided with a pinion 41 (see Figs. 3 and 6), which rotates on said shaft and which has a clutch member 42. A second pinion 43 is also rotatably mounted on said shaft, and has a clutch member 44. A central clutch member 45 is keyed to the shaft 40 and is adapted to engage either the clutch member 42, or the clutch member 44. The pinion 43 engages a gear 46 on a shaft 47 (see Fig. 6), which shaft is rotated in one direction when the clutch member 45 100

engages the clutch member 44. The pinion 41 engages an idle pinion 48 (see Figs. 3 and 8), and this idle pinion engages a gear 49 on the shaft 47 so that when the clutch member 45 is in engagement with the clutch member 42, the shaft 47 will be rotated in the opposite direction. The shaft 47 is provided with a sliding clutch member 50 (see Fig. 6) which is adapted to engage a clutch member 51 on the beveled gear 52, loosely mounted on the shaft. When these clutch members are in engagement, the beveled gear 52 is rotated, and this rotates the beveled gear 53 on the shaft 54 and the gear 55 connected with said shaft, said latter gear engaging a gear 56 on the screw threaded shaft or rod 21 so as to rotate it. It will thus be seen that by means of the clutch member 45 and the clutch member 50, the screw threaded rod or shaft 21 may be rotated forward or backward so as to lift or lower the nut 22, and thus lift or lower the cutting element 8.

The cutting element may be lifted when it is desired to move it from place to place and 25 may be lowered to the floor when it is desired to make a cut.

The cutter arm of the cutting element is moved laterally by the following mechanism: The main frame 1 is provided at the rear 30 thereof with a rack 57 (see Figs. 5 and 7). This rack is engaged by a pinion 58, loosely mounted on the shaft 59. This pinion is driven from the motor. In the construction shown the pinion 58 is provided with a clutch 35 member 60. A sliding clutch member 61 is feathered to the hub 62 of the gear 63. The gear 63 engages a pinion 64 on a short shaft 65, and a gear 66 on this short shaft engages a pinion 67 on the shaft 47. When the shaft 40 47 therefore is driven as hereinbefore set out, and the clutch member 45 is in engagement with the clutch member 42, the gear 63 and the clutch member 61 will be driven in one direction, and if this clutch member 61 is 45 brought into engagement with the clutch member 60, the pinion 58 will be rotated in one direction and will move along the rack 57, so as to rotate the moving frame about the parts 5 and 6 to move the cutting element laterally. 50 When it is desired to move the cutting element in the opposite direction laterally, the clutch member 45 is disconnected from the clutch member 42 and connected with the member 44. This reverses the direction of the 55 movement of the shaft 47 and reverses the pinion 58, and causes the cutting element to be moved laterally in the opposite direction.

When it is desired to move the entire device backward or forward at slow speed, the 60 clutch member 68 (see Fig. 5), which is feathered to the shaft 59, is moved to engage the clutch member 69 connected with the gear 70, said gear being loosely mounted on the shaft 59. A pinion 71 which is connected 65 with the hub 62, engages a gear 72 on a short

shaft. This shaft has a pinion 73 also connected with it, and this pinion engages the gear 70. When the clutch member 68 is connected with the clutch member 69 it will be seen that the shaft 59 is driven at a reduced speed from the gear 63 which is connected with the motor as hereinbefore set out. The shaft 59 is provided with a beveled pinion 74 (see Figs. 5 and 7) which beveled pinion engages a beveled pinion 75 on the shaft 76. A beveled pinion 77 is connected with the shaft 78 and engages the beveled pinion 75 so that the shaft 78 is rotated when the shaft 59 is rotated. The shaft 78 (see Fig. 5) has a beveled pinion 79 which engages a beveled pinion 80 on the axle 81, carrying the forward wheels 2. It will thus be seen that when the shaft 78 is rotated in one direction the entire device will be moved forward, and when the shaft 78 is rotated in the opposite direction, the entire device will be moved backward. The forward and backward movement of the shaft 78 is controlled by the clutch member 45 as hereinbefore described in connection with the driving of the pinion 58.

If it is desired to drive the entire machine at a high rate of speed, the clutch member 68 is moved out of engagement with the clutch member 69 and the clutch member 82 (see 95 Figs. 1 and 3) feathered on the shaft 31, is moved into engagement with the clutch member 83 connected with the beveled gear 84. This connects the beveled gear 84 with the shaft 31 which is driven directly from the motor by the pinion 29 and the gear 30 keyed to the shaft 31. The beveled pinion 84 engages a beveled gear 85 on the shaft 76, and thus drives said shaft and the pinion 75, and the pinion 77, and the shaft 78, and the 100 pinions 79 and 80 at a high rate of speed.

The cutter of the cutting element may be of any suitable form and is hereby shown as a cutting chain 86 (see Fig. 14). This cutter, whatever its form, is driven in the 110 following manner: The motor 26 drives the pinion 29 and the gear 30 and the shaft 31. A shaft 87 is provided with a clutch member 88 keyed thereto. When the clutch member 82 is moved to engage the clutch member 88, the shaft 31 is connected with the shaft 87 so as to rotate it. The shaft 87 is provided with a flexible or universal joint 89. The end of this shaft 87 is hollow and a shaft section 90 slides therein and is feathered thereto so as to rotate therewith, but is free to slide therealong to compensate for variations in length due to the movement of the cutting element. The shaft section 90 is connected by a universal joint 91 with the shaft 92 (see Fig. 11) which carries a pinion 93, which engages a beveled gear 94 on the shaft 95. The latter shaft carries the sprocket wheel 96 which drives the cutting chain 86.

The cutter is fed to the coal by means of a 130

cable 97 on a drum 98 (see Figs. 2 and 11 and 14). This cable is fastened to a suitable jack or other fixed support as shown in Figs. 19 to 23 inclusive, and then the drum is rotated to wind the cable thereon. This drum is rotated by the following mechanism: The motor 26 through the gears and pinions 29, 30, 32, 33, 35 and gear 36 drives the member 38 of the friction clutch and the shaft 99 through the planetary gear 100 of any ordinary form, and thus giving a proper reduction of speed. A gear 101 on shaft 99 engages a gear 102, rotating loosely on the shaft 105, having a clutch member 103. A clutch member 104, feathered to the shaft 105, is adapted to be moved to be brought into engagement with the clutch member 103 so as to drive said shaft 105. This shaft is connected by a universal joint 106 with a shaft section 107. The shaft section 107 (see Fig. 11), is feathered to a hollow shaft section 108, and this hollow shaft section is connected by a universal joint 109 with the shaft 110, carrying the beveled pinion 111, which beveled pinion meshes with the beveled gear 112 rotatably mounted on the section 113 of the frame of the cutting element. The beveled gear 112 engages a beveled gear 114 connected with the shaft 115, said shaft being mounted in a section 116 of the frame of the cutting element, said section 116 having a pin 117 which fits into a frame piece 118. The shaft 115 has a pinion 119 (see Fig. 13) which engages an internal gear 120 connected with the drum 97, said drum rotating about the frame section 116. It will thus be seen that when the drum 116 is rotated, the cable will be wound thereon and the machine fed to the coal. The internal gear arrangement also reduces the speed of the feed, and the parts are arranged so as to secure the proper speed of feed of the cutter to the material to be cut.

The cable 97 (see Figs. 12 and 14), passes over a guide pulley 121 and then passes around a second guide or direction changing pulley 122. This latter pulley is mounted in a frame 123, which is pivoted at its end by means of the pivots 124 and 125 with the frame of the cutting element. This arrangement permits the cable to work freely when leading off in any direction from the machine.

The device is preferably arranged so that the cutter arm may project forward or may be moved around to either side. This result is secured in the following manner: The part 126 (see Figs. 2 and 14) from which the cutter arm projects, and which carries the drum 98, is provided with a series of holes 127. A frame piece 128, located above the part 126, is free to move with relation thereto, and projecting through it is a locking device 129. This locking device passes into one of the holes 127 depending upon the po-

sition of the parts. It will thus be seen that this locking device may be removed and the cutter arm moved around it any desired angle at either side of the straight forward position, and then locked in this position by placing the locking device 129 in one of the holes 127. The parts are arranged so that the cutting element can be moved through an arc of 180 degrees. The frame piece 128 is cut out for this purpose as shown in Fig. 14, and has the laterally projecting parts 130.

When the machine is being used as shown for example in Figs. 18 to 21, the cable 97 is fastened to a fixed device 131 as shown in Fig. 19, the cutter arm being shown in the position indicated. The drum is then rotated to wind the cable thereon, and this fits the cutter to the coal as shown in Fig. 20. The jack or fixed device 131 is then moved to the position shown in Fig. 20, and the cable wound upon the drum, and this fits the cutter to the coal until it reaches the position shown in Fig. 21. The jack or fixed device 131 is then moved to the position shown in Fig. 21 and the drum rotated to move the machine back to finish the cut.

It will be noted that when the body of the machine is at the beginning of its cut as shown in Fig. 20, the cutter arm projects to one side at an angle to the body of the machine and that when it reaches the end of its lateral cut as shown in Fig. 21, it projects toward the other side or at an angle in the opposite direction as shown in said Fig. 21, and this gradual movement of the cutter arm during the cut must be brought about by some suitable mechanism. As herein shown this result is secured by means of the arms 132 and 133. These arms are connected to the projections 130 of the piece 128 by means of a universal or flexible or ball and socket joint, as shown in Fig. 17. In this construction each arm has a cap 134 which engages a ball 135, the cap being adjustably connected with the arm in any desired manner as by being connected with the screw threaded part 136. This permits the easy removal of the socket from the ball. The arms 132 and 133 are arranged in sections, pivotally connected together at 139 so that the sections have relatively vertical movement, but not lateral movement. The ends of the arms are pivoted at 137 and 138 to the main stationary frame 1 of the machine. It will be noted that these arms 132 and 133 are closer together at their inner ends than they are at their outer ends. The arms are therefore not parallel, but are diverging from their inner ends toward their outer ends, and hence when the machine is moved laterally to feed it to the coal, they automatically cause the cutting element to take the various positions as shown in Figs. 20 and 21 and move gradually through the angle necessary.

sary to bring them into these different positions.

In some places there are hard spots in the coal and it is necessary to cut above the floor of the mine. In such event the cutter arm can be held in any desired position by tightening down the nut 22, the arms 6 holding the cutting element in this desired position while it is being fed to the coal.

It sometimes happens that the floor of the mine is uneven and that the cutter must therefore be free to move up and down to compensate for this unevenness as it moves across the floor. The present invention provides automatically for this up and down movement. It will be noted that the supporting arms 6 are pivoted on the frame as they are connected to the rock shaft 16. The controlling arm 19 which is connected with the rock shaft 16 and hence with the arms 6 (see Figs. 3 and 6) is controlled by the nut 22. When the nut is screwed down, this arm is moved down and rocks the rock shaft 16 to lift the arms 6 and the cutting element. When the machine is cutting coal this nut 22 may be loosened up a sufficient amount so as to leave a space between it and the socket or hub 20 of the controlling arm 19. It will thus be seen that when the cutting element comes to a high point in the floor, it can slide up over it, and during this action the hub or socket 20 of the controlling arm 19 simply moves up and down in the space left between it and the nut 22. It will be noted that in this device the supporting arms 6 project at an angle and the cutter of the cutting element projects at another and a different angle, the apparatus having means for securing this result. This construction permits the machine to cut in a narrow entry as it permits it to be set down between the track and wall when the space is narrow as shown for example in Fig. 22. The machine can be placed in the position shown in this figure and then moved forward into the coal and then moved across the end of the track to make the complete cut. It will further be noted that in this construction the mechanism is supported upon the movable frame 3 which is pivotally mounted upon the main supporting frame. It will further be noted that the motor and gears project out on one side of this pivot and the cutting element on the other side, the one thus counterbalancing the other as the cutting element swings from one position to another. It will further be noted that the gearing for the operation of the different parts of the cutting element is a straight line gearing running out straight from the motor to the part to be driven. In this construction also all driving connections for slow motions go through the friction clutch which acts as a safety device. It will further be noted that there are certain characteristics in this device that permit it to make the entire cut above referred to, such for ex-

ample as shown in Fig. 22. Since the cutter arm by its method of support is in a straighter position than the arms which support it when it is at one side as shown in Fig. 22 it will thus be seen that the cutting element can be set down between the wall and the track so that the bottom of the cutting element will be below the upper part of the rails. The entire machine can then be moved forward by the cable 97 to make the initial cut, and this initial cut moves the cutting element beyond the ends of the rails, and the cutting element can then be moved across in front of the rails, and then the entire machine can be moved back, the cutting element passing between the wall of the entry and the rails on the opposite side. In other words in this construction the bottom of the cutting element can be moved below the top of the rails while a part of the cutting element is opposite the rails, and the entire machine can then be moved forward on the rails until the sumping cut is made, and then the cutting element can be moved sideways in front of the rails with its bottom portion still below the top of the rails. It can then while in this position, be moved back so part is opposite the rails to finish the final cut, the final cut being the portion which is shown uncut in Fig. 21.

I claim:

1. A mining machine comprising a supporting frame, a cutting element movable on the mine floor independently of said supporting frame, and three different forms of connection between said cutting element and the supporting frame, one being a supporting connection permitting pivotal movement of said cutting element, one being a driving connection, and one being a controlling connection for controlling the angular position of the cutting element relative to the supporting connection.

2. A mining machine comprising a supporting frame, a cutting element slidably supportable on the mine floor independently of said frame, two arms connected with said cutting element, a rock shaft on said supporting frame with which said arms are connected, means for rocking said shaft to lift and lower the cutting element, and feeding mechanism for feeding the cutter of the cutting element to the material to be cut.

3. A mining machine comprising a base, a supporting frame pivotally mounted thereon to swing in a horizontal plane, a cutting element, a plurality of arms connected with said supporting frame and projecting beyond said supporting frame and engaging the supporting frame intermediate their ends, and a connection between said arms and said cutting element, a motor on said supporting frame, and a driving connection between said motor and said cutting element.

4. A mining machine comprising a base, a supporting frame pivotally mounted on said

- base to swing in a horizontal plane, two arms located in substantially the same horizontal plane pivotally connected to said base at separate points and projecting beyond said base and supporting frame, a shaft carried by said frame having a pivotal connection intermediate said arms, the arms and shaft adapted to be moved about their pivotal points, a cutting and feeding element connected with said arms and provided with a cutting device and a feeding device for feeding the same, and an operative connection between said shaft and said cutting device during all of the various positions of said arms.
5. A mining machine comprising a main frame, a motor on said frame, a cutting and feeding element movably supported on the ground independent of said frame and in a different vertical plane therefrom, said cutting and feeding element provided with a movable cutter for cutting the material, a supporting connection between said frame and said cutting and feeding element, a separate controlling connection between said cutting and feeding element and said main frame for controlling the position of the cutting and feeding element relative to said supporting element, and a driving connection between said motor and said cutter adapted to drive the cutter in the various positions of the cutting and feeding element.
6. A mining machine comprising a base, a frame movable angularly on said base, supporting arms connected with said frame and projecting therefrom, a cutting element movably supportable on the ground and with which said arms are connected for pivotal movement transversely thereof, a cutter arm forming a part of said cutting element, said cutter arm during the major part of its cutting movement projecting at an angle with relation to the surface on which the machine rests different from the angle of said supporting arms.
7. A mining machine comprising a base, a rocking frame having angular movement on said base, means for moving said frame relative to said base, arms connected with said movable frame and projecting therefrom, a cutting element pivotally connected with said arms for movement transversely thereof, a motor on said moving frame, operative connections between said motor and said cutting element, said motor acting as a counterbalance for the cutting element as the frame is moved angularly on said base.
8. A mining machine comprising a base, a rocking frame having angular movement on said base, means for moving said frame relative to said base, arms connected with said movable frame and projecting therefrom, a cutting element pivotally connected with said arms for movement transversely thereof, actuating mechanism for said arms and cutting element, said actuating mechanism arranged to act as counterbalance for the arms and cutting element as the moving frame is moved angularly on said base.
9. A mining machine comprising a base, a supporting frame pivotally mounted on said base to swing in a horizontal plane, a cutting element, a plurality of arms connected with said supporting frame so as to be free to move in a substantially vertical plane, a connection between said arms and said cutting element, a motor on said supporting frame, an operative connection between said motor and said arms so that they may be moved about their pivotal connection, and a feeding mechanism separate from said arms for feeding the cutter of the cutting element to the material to be cut.
10. A mining machine comprising a supporting frame, a cutting element, a plurality of arms connected with said supporting frame and pivoted on a transverse axis so as to be free to move in a substantially vertical plane, a connection between said arms and said cutting element, a controlling device for said arms, a threaded part adapted to engage said controlling device and move it when actuated, and means for actuating said threaded device.
11. A mining machine comprising a supporting frame, a cutting element, a plurality of arms connected with said supporting frame so as to be free to move in a substantially vertical plane, a connection between said arms and said cutting element, a controlling device for said arms, a threaded part adapted to engage said controlling device and move it when actuated, means for actuating said threaded device, said threaded device adapted to be moved out of the way of said controlling device when the cutter is in operation so as to leave the cutting element free to move to accommodate itself to unevenness in the floor.
12. A mining machine comprising a supporting device, supporting arms connected therewith, a cutting element, a rotating part eccentrically mounted on said cutting element, and a connection between said rotating part and said arms by means of which the cutting element is supported, said rotatable part adapted to be moved to adjust the cutting element with relation to the said arms.
13. A mining machine comprising a supporting device, supporting arms connected therewith, a cutting element, a rotating part eccentrically mounted on said cutting element, and a connection between said rotating part and said arms by means of which the cutting element is supported, said rotatable part adapted to be rotated and also adapted to be rocked so as to adjust the cutting element with relation to said arms.
14. A mining machine comprising a truck, a cutting element separate from the truck,

arms connected with the truck and with the cutting element for moving the cutting element, a motor on the truck, two driving connections between said motor and said truck, comprising four shafts, two of said shafts having their ends adjacent beveled gears on such adjacent ends, a shaft at an angle to the two shafts having a beveled gear which engages the beveled gears on said shafts, said 10 angular shaft provided with a second beveled gear, a fourth shaft also provided with a beveled gear engaging the beveled gear on the angular shaft, and means for connecting and disconnecting the beveled gear on the fourth shaft with its shaft.

15. A mining machine comprising a supporting frame, a cutting element in front of said frame and supportable on the mine floor independently thereof, arms connecting said 20 cutting element with said supporting frame, said arms free to move in a substantially vertical plane, a motor on said frame, a connection between said motor and said arms for moving the arms to lift the cutting element, 25 and means for permitting the cutting element freely to move vertically when the cutting device is in operation so that it automatically adjusts itself to the unevenness in the floor.

16. A mining machine comprising a truck 30 adapted for movement on rails, the rails extending in proximity to the wall of material to be cut, a cutting element having a bottom support, movable arms connecting the cutting element with the truck, means for lowering 35 the cutting element at one side of and below the top of the tracks so that its bottom will be supported on the mine floor independently of said truck, means for then moving the cutting element forward to make the 40 sumping cut and for moving it laterally to make the cross cut, and means for moving the cutting element back at one side of the rails with its bottom portion still supported on the ground below the top of the rails to 45 finish the cut, whereby a narrow entry may be cut.

17. A mining machine comprising a truck adapted for movement upon rails, a cutting element normally supported by said truck 50 and provided with a shoe, means for lowering the cutting element at one side of the rails so that its cutting portion will be below the top of the rails, and with its shoe in supporting relation with the ground, means for moving 55 the entire machine forward to make the sumping cut, and means for moving the cutting element across in front of the rails to make the lateral cut, whereby a narrow entry may be cut.

60 18. A mining machine comprising a base, a supporting frame pivotally mounted thereon to swing in a horizontal plane, lifting means carried by said supporting frame and projecting therebeyond, a cutting element 65 mounted on the forward end of said lifting

means, a pair of arms pivotally connected between said cutting element and said base for controlling the relative angular position of the two last named elements, a motor on said supporting frame, and means operatively connecting said motor with said cutting element. 70

19. A mining machine comprising a base, a supporting frame pivotally mounted thereon to swing in a horizontal plane, lifting means carried by said supporting frame and projecting therebeyond, a cutting element mounted on the forward end of said lifting means, a pair of arms pivotally connected between said cutting element and said base for controlling the relative angular position of the two last named elements, a motor on said supporting frame, and means operatively connecting said motor with said cutting element, comprising a shaft substantially in the same horizontal plane as said lifting means. 75 80

20. A mining machine comprising a base, a supporting frame pivotally mounted thereon to swing in a horizontal plane, a plurality of arms carried by said supporting frame and projecting therebeyond, a cutting element mounted on the forward end of said arms, a pair of arms pivotally connected with said cutting element and said base for controlling the relative angular position of the two last named elements, a motor on said supporting frame, and means operatively connecting said motor with said cutting element. 90

21. In a mining machine, the combination with a truck adapted to travel along a mine track, a cutting element supportable on the mine floor and including an elongated chain cutter frame pivotally mounted on said truck and having supporting connection with the rear end of said cutting element to raise the same or to permit the same to rest on the mine floor at the sides and end of said track and a separate connection between said truck and the rear end of said cutting element for controlling the angular position of said cutter relative to said truck. 100 105

22. In a mining machine, the combination with a truck adapted to travel along mine track, a cutting element supportable on the mine floor and including an elongated chain cutter frame pivotally mounted on said truck and having supporting connection with the rear end of said cutting element to raise the same or to permit the same to rest on the mine floor at the sides and end of said track, a separate connection between said truck and the rear end of said cutting element for controlling the angular position of said cutter relative to said truck, and means for driving said cutting mechanism while supported on the ground. 115 120

23. A mining machine comprising a base, a supporting frame pivotally mounted thereon to swing in a horizontal plane, lifting means carried by said supporting frame and projecting therebeyond, a cutting element 130

mounted on the forward end of said lifting means, a pair of arms pivotally connected between said cutting element and said base for controlling the relative angular position of the two last named elements, a motor on said supporting frame, means operatively connecting said motor with said cutting element, and means for locking the cutting element in various angular positions relative to said controlling arms.

Signed at Chicago, county of Cook, and State of Illinois, this third day of February, 1921.

CHARLES E. DAVIS.
